UNITED STATES PATENT OFFICE.

ALFRED JOHN BARNES, OF LONDON, ENGLAND.

APPARATUS FOR DEODORIZING AND FILTERING PETROL SPIRIT.

No. 898,545.

Specification of Letters Patent. Patented Sept. 15, 1908.

Application filed April 18, 1907. Serial No. 368,927.

To all whom it may concern:

Be it known that I, ALFRED JOHN BARNES, subject of the King of Great Britain, residing at 11 Queen Victoria street, in the county of London, England, have invented Apparatus for Deodorizing and Filtering Petrol Spirit.

This invention has for its object the construction and adaptation of a container or vessel fitted to the spirit feeding mechanism of a motor omnibus, motor car or the like, and through which the petrol or other spirit from the tank is caused to pass.

In carrying the invention into effect I provide a metal case or container, preferably of cylindrical shape, and fit therein an inner and an outer cylinder capable of removal therefrom. These two cylinders are provided with small perforations in their sides, and in the annular space between them is packed or placed a special preparation adapted for filtering the petroleum or other spirit, and deodorizing the fumes therefrom. To prevent the said preparation passing through the perforations in the two cylinders, the inner one is lined outside, and the outer one inside, with fine wire or other gauze permitting of the passage of the spirit only. The case or container is fitted with a cover packed and bolted tightly thereto, and forming a liquid tight joint within a cylinder, and the top of this cover is formed with a coupling joint for connecting up the inlet pipe from the tank to the interior of the inner cylinder.

In the accompanying drawings, Figure 1 represents a vertical section of the container or case and internal cylinders, and Fig. 2 is a horizontal section thereof.

a is the said container or case and b is the cover fitted tightly thereto by the bolt c and packing ring d. The cover is formed with a screw coupling joint or inlet e, for connecting the pipe from the tank feeding the petrol to the engines.

f is the outer cylinder having perforations f' in its sides and closed at g, near the bottom of the container, while its upper end fits tightly within a rim or recess h formed on the cover.

i is the inner cylinder having perforations i' and resting in a recess j at the bottom of the container, while its upper end fits tightly around a rim k, on the cover.

l is the outlet from the container for leading the petrol by a pipe connected thereto to the carbureter or to the engines.

m is a suitable preparation, preferably in the form of a powder, which preparation is packed or placed in the annular space n between the cylinders f and i, and o is the wire gauze fitted to the outside of the latter, p, being the gauze similarly fitted to the inside of the former for preventing in each case the passage of the material through the perforations in the cylinders.

The petrol or other spirit fed from the tanks passes through the inlet e, into the inner cylinder i, from which it escapes through the perforations i' into the space n and thoroughly mixes with the preparation m therein. From the space n, the petrol then passes through the perforations f', into the outer case or container a, which it finally leaves by the outlet l on its way to the carbureter or engine. The spirit then passes through the preparation, takes up or incorporates with it the essence of the said preparation and becomes thoroughly deodorized thereby, destroying the fumes from the spirit and also those due to any excess in the lubrication of the engines.

What I claim, and desire to secure by Letters Patent of the United States is:—

1. In a filtering and deodorizing apparatus, a container having a single centrally located recess in the bottom and a lateral outlet near the top, a removable cover having a central inlet nozzle upon its outer face and two concentrically located rims on its inner face, two internal perforated cylinders of unequal length within the container, the inner and longer cylinder resting within the bottom recess and extending from there, up to the inner face of the cover where it surrounds the smaller of the concentric rims thereon, while the outer perforated cylinder fits within the larger of the concentric rims and, being shorter than the other cylinder, terminates above the level of the bottom of the container, an annulus seated to the bottom of said outer cylinder and surrounding the inner cylinder, whereby a free space is provided both at the bottom and at the side of the container, whereby said cylinders may be removed from said container, and whereby said cylinders may be separated, and a filtering and deodorizing material between said cylinders.

2. In a filtering and deodorizing apparatus, a vertically disposed cylindrical container, a centrally locked circular recess adapted to catch sediment formed by the an-

nular up-standing rib, said container having a lateral outlet at the top of its side, a removable cover having a central inlet nozzle upon its outer face and two concentric lock 5 rims on its inner face, two internal concentric perforated cylinders of unequal length within said container, the inner and longer cylinder resting within said bottom recess where it is held against lateral displacement 10 by said up-standing rib, said inner cylinder extending upwardly to said cover and fitting around the inner of the concentric rims thereof, the outer of said internal cylinders fitting within the outer of said concentric rims and 15 terminating at its lower end above the level of the top of said up-standing rib, said lower end being provided with an inwardly pro-

jecting flange, an annulus secured near the bottom of said inner cylinder and spaced from said up-standing rib, removable means 20 to fasten said flange to said annulus whereby the free space for the collection of sediment is provided between the bottom of said container and the bottom of said inner cylinder and a filtering and deodorizing material be- 25 tween said cylinders.

In testimony whereof I have signed my name to this specification in the presence of two subscribing witnesses.

ALFRED JOHN BARNES.
